UNITED STATES PATENT OFFICE

120,648

DESIGN FOR A COMBINATION PASTE DISPENSER AND TOOTH BRUSH HOLDER

James M. Nixon, Asheville, N. C.

Application March 22, 1939, Serial No. 83,772

Term of patent 3½ years

To all whom it may concern:

Be it known that I, James M. Nixon, a citizen of the United States and residing in the city of Asheville, county of Buncombe and State of North Carolina, have invented a new, original, and ornamental Design for a Combination Paste Dispenser and Tooth Brush Holder, of which the following is a specification, reference being had to the accompanying drawing, forming a part thereof.

I claim:

The ornamental design for a combination paste dispenser and tooth brush holder, as shown.

JAMES M. NIXON.
